UNITED STATES PATENT OFFICE.

CHARLES WESLEY JONES, OF GLEN RIDGE, NEW JERSEY, ASSIGNOR TO SONS-CUNNINGHAM REED & RATTAN CO. INC., OF NEW YORK, N. Y., A CORPORATION OF NEW YORK.

DESIGN FOR A CHAIR FRAME.

Application filed August 25, 1928. Serial No. 27,959. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for a Chair Frame, of which the following is a specification, reference being had to the accompanying drawing, forming part thereof.

The drawing shows in perspective view a chair frame embodying my new design.

I claim:

The ornamental design for a chair frame, as shown.

In witness whereof, I have hereunto set my hand.

CHARLES WESLEY JONES.
